ARTHUR T. YATES, OF GARDENVILLE, NEW YORK, ASSIGNOR TO BUFFALO FORGE COMPANY, OF BUFFALO, NEW YORK.

PUNCHING MACHINE.

Application filed October 2, 1925. Serial No. 60,027.

This invention relates to punching machines, or forming, or blanking presses of the kind in which a reciprocatory member is actuated by power driven means to force a punch or tool toward or through the work, and more particularly to machines or presses of this kind in which the punch or the part carrying the same may be disconnected from its power driven means to enable the punch to be accurately positioned with reference to the work.

The objects of this invention are to provide a machine of this kind of improved construction which is so organized that the punch head or plunger may be moved toward and from the work and connected with the power driven means with the use of only one hand, the other hand being thus left free to use in positioning the work; also to provide a machine of this kind with friction means for counterbalancing the weight of the plunger or head, so that the plunger will remain in any position in which it may be set; also to provide a machine of this kind with adjustable means for disengaging the punch from its power driven means at different positions of the stroke of the plunger, so that the stroke of the plunger or head may be decreased when the machine is used on thin material; also to provide a machine of this kind which is so constructed that the power driven ram may be connected with the plunger regardless of the position of the plunger in its path of movement; also to provide means for forming a connection between the ram and the head which connection will not raise the plunger or head until the down stroke of the plunger is completed; also to so construct the connection between the ram and the head that this connection can easily be adjusted as desired and to provide adjustments which eliminate the necessity for accurate machining of several of the parts of this connection; also to provide a machine of this kind with cushioning or shock absorbing means which become effective just as the metal is being sheared and prevent sudden jerking of the plunger or head at the end of the down stroke of the plunger; also to improve the construction of

machines of this kind in other respects hereinafter specified.

In the accompanying drawings, Fig. 1 is a longitudinal central sectional elevation of the front end of a punching machine embodying my invention.

Fig. 2 is a similar central sectional elevation thereof showing some of the parts in different position.

Fig. 3 is a sectional plan view thereof on line 3—3, Fig. 1.

Fig. 4 is a fragmentary sectional elevation thereof on an enlarged scale on line 4—4, Fig. 3.

Fig. 5 is a fragmentary longitudinal central sectional elevation thereof similar to Figs. 1 and 2 and showing some of the parts in another position.

Fig. 6 is a fragmentary front elevation thereof, partly broken away.

Fig. 7 is a fragmentary longitudinal sectional elevation thereof on line 7—7, Fig. 6.

Fig. 8 is a fragmentary side elevation thereof.

Fig. 9 is a sectional elevation thereof on line 9—9, Fig. 3, on an enlarged scale.

Fig. 10 is a fragmentary sectional elevation thereof on line 10—10, Fig. 5.

The accompanying drawings illustrate one embodiment of my invention applied to a punching machine for punching holes in metal or other work, but it will be understood that it is not intended to limit my invention to use only in connection with punching machines, since the same can be used on various kinds of presses, such as blanking or forming presses, or shearing machines, and the words "punching machine" as used in the specification and claims, is intended to include such presses and machines to which this invention is applicable.

A represents the punch or other tool, and B the die with which the tool A cooperates or into which the punch enters after passing through the work X, which may be positioned upon the die B. C represents the frame of the punching machine and D the usual rocker arm, which is pivoted at E on the frame C of the machine. The drive

means for imparting an oscillating motion to the rocker arm D are not shown, since these means may be of any suitable construction. All the parts so far described are commonly used in connection with punching machines, and of themselves constitute no part of this invention.

15 represents a guide or bearing member secured on the front part of the frame C of the machine, which frame may include two substantially parallel upright plates, as shown in Fig. 3, to which the guide or bearing member 15 is secured by means of bolts 16 or other suitable means, which extend through the two plates of the frame of the machine, and a rearwardly extending part 17 entering between the two plates of the frame C. The guide member also has forwardly extending upright bearing flanges 18 or walls 18 which are spaced apart, and a front wall or plate 19, suitably bolted or otherwise secured to the front faces of the bearing flanges or walls 18 of the guide member.

25 The punch or tool A is secured to the lower end of a reciprocating tool carrying head or plunger 20, which is guided in its vertical movement by the front, side and rear walls of the guide member 15, the plunger or head as shown being of substantially U-shaped construction, including a pair of upwardly extending arms or parts 21, connected at their lower ends by the portion of the head or plunger 20 on which the tool or punch A is removably held. 22 represents a wear plate or shim interposed between one of the upright arms 21 and the side wall 18 of the bearing block 15, and 23 represents a bearing or thrust block interposed between the upright arms 21 of the plunger or head and resting upon a horizontal face extending between the upright arms 21, and the bearing block 23 being held in place by means of screws or bolts 24 extending through the upright arms 21 and from opposite sides of the plunger or head and engaging the opposite sides of the bearing block 23.

50 Reciprocating movement in opposite directions is imparted to the plunger or head 20 by means of a power driven member or ram 27, which is pivotally mounted on the rocker arm D at the upper end of the ram, and receives power therefrom, and which is adapted to move into and out of engagement with the tool carrying head or plunger. In the particular construction shown, the lower end of the power driven member or ram is adapted to seat on a rounded face 28 of the bearing or thrust block 23 of the tool carrying head 20. In the embodiment of the invention shown in the drawings, the ram is pivoted at its upper end on the forward end of the rocker arm D, a pivot or pin 29 being employed for this purpose which

extends through two flanges 30 of the rocker arm D, and the upper end of the ram bears against a bearing block 31 secured on the rocker arm D between the flanges 30 thereof. It will be understood that the rocker arm 70 D is oscillated continuously through the medium of a motor or other source of power, and thus imparts lengthwise movement to the ram 27, which movement, however, is only imparted to the tool carrying head or plunger 20 when the ram is in engagement with the bearing block 23 thereof, and when the rocker arm is not thus in engagement with the plunger, the ram is adapted to move lengthwise in a space or recess 32 formed in the rear portion of the guide member 15. The ram occupies a position between the upright arms 21 of the plunger or head 20.

75 The ram may be held out of engagement with the plunger or head 21 by means of a ratchet or detent link or latch 35, pivoted at 35^a in a recess in the front face of the ram and having a notch 36 near its other end which is adapted to engage with a detent or latch holding plate or member 37 secured on the front wall or plate 19 of the guide member 15, the plate 37 extending across an opening 38 in the front wall 19 of the guide member. Thus when the notch of the detent link 35 is in engagement with the ratchet plate 37 as shown in Figs. 2 and 5, the ram 27 is held out of engagement with the plunger and reciprocates in the recessed portion 32 of the guide member, the detent link 35 swinging about its connection with the holding plate 37 during this movement of the ram. When, however, the detent lever 35 is released from its connection with the holding plate 37, the ram is yieldingly moved into engagement with the tool carrying member by any suitable means, such, for example, as a spring 39, which in the construction shown is in the form of a leaf spring secured at one end to the bearing or wear block 31 of the rocker arm D, and the other, or free end of which bears against the rear face of the ram 27, and thus moves the ram into its operative position shown in Fig. 1 when the detent link 35 is released from its holding plate 37.

80 It is desirable after each operating stroke of the plunger 20 that the ram be moved automatically into inoperative position in which the link 35 engages the plate 37, so that when this link is disengaged from its holding place, the machine will actuate the punch A only once. In the particular construction shown for this purpose, the ram 27 is provided with a projecting part or knock-out pin 42 which may be formed integral with the ram 27 or which may, as shown in the drawings, be formed of a separate part secured in a hole in the ram 27 and extending forwardly therefrom. The upper face of the knock-out pin 42 is adapt-

ed to engage with a projection or part on a fixed part of the machine, for example, with the rearwardly projecting end of a knock-out lever 43, which is pivoted at 44 on the upper portion of the front plate or wall 19 of the side member. The forwardly extending arm of the knock-out lever is preferably, though not necessarily, made to cooperate with adjusting means whereby the rearwardly extending knock-out projection of the lever 43 may be raised or lowered to control the releasing of the ram 27 from the plunger at the desired part of the stroke of the plunger. In the particular construction shown, the forward end of the knock-out lever 43 bears against an adjustable screw 46 suitably adjustably secured in a forwardly extending projection 47 of the front wall or plate 19 of the guide member. In the operation of the knock-out mechanism, Fig. 1 shows the knock-out projection 42 and lever 43 in engagement, the plunger 20 having reached the upper limit of its stroke. Upon further upward movement of the ram 27, the knock-out projections 42 and 43 engage and cause the ram to swing into the position shown in Fig. 2, against the action of the spring 39. The swinging back of the ram 27 also causes the notched portion 36 of the detent link 35 to engage the holding plate 37.

In order to cause the power driven member or ram 27 to raise the tool carrying head or plunger 20 after completing the downward stroke, suitable resilient means are provided on the ram which engage with parts on the plunger only when the ram is properly seated on the plunger. These means may be of any suitable or desired construction and may be organized as follows:

The ram 27 is provided at each side with an upwardly extending arm 50, the two arms being secured on a pin or shaft 51 pivoted or journaled on the ram. The upwardly extending arms 21 of the plunger or head 20 are provided with recessed portions 52 into which the upwardly extending arms 50 are adapted to enter, and in which the arms 50 are adapted to engage with parts of the plunger or head, for example, set screws 53 may be secured in the upper ends of the arms 21 of the plunger, the set screws extending downwardly into the recesses 52 and are adapted to be engaged by the upper ends of the arms 50, the set screws 53 being adjustable vertically in virtue of their threaded engagement with the arms 21 of the plunger, and are held in their adjusted positions by means of lock nuts 54, see Figs. 6 and 7. The arms 50 may be resiliently held in their upright or operative positions by any suitable or desired means. In the particular construction shown for this purpose, a pin or projection 56 is arranged on the shaft 51 and extends rearwardly therefrom through a re-

cess 57 in the rear face of the ram 27, and the outer end of this pin 56 is connected with one end of the spring 58, and other end of which is connected to a pin 59 secured on the ram 27. The spring 58 normally draws 70 the pin 56 into a position against a stop face 60 of the recess 57, and when the pin 56 is in engagement with the stop face 60, the lifting arms 50 are in their upright or operative position. Any other resilient means for holding the arms 50 in their upright positions may be employed if desired. By providing resilient means for holding the arms 50 in their upright or operative position, it will be seen that if the detent link 35 is lifted at a 75 time when the ram 27 is above the position in which it can operatively seat on the bearing face 28 of the plunger or head, the yielding lifting arms 50 will permit the spring 39 to move the ram toward its operative position, the lifting arms being moved backwardly against the action of the spring 58, by the engagement with the sides of the set screws 53 or other parts of the plunger, and as soon as the ram seats on the bearing plate 90 23 of the plunger, the lifting arms 50 will be quickly moved by the spring 58 into their operative positions under the set screws 53, and when the ram begins its upward movement, the lifting arms engaging the set 95 screws 53 raise the plunger until the knock-out projection or pin 42 engages the rear extension of the knock out lever 43, whereupon the ram 27 will be swung rearwardly during which movement the upper ends of the lifting arms 50 slide out of engagement with the ends of the set screws 53. By providing set screws with which the upper ends of the lifting arms engage, this part of the machine 100 can be readily adjusted so that the engagement of the lifting arms with the plunger or head can be properly timed.

The construction of the punching machine described makes it possible to lower and raise the tool carrying head or plunger 20 toward 110 and from the work, while the ram 27 is out of engagement therewith, so that an accurate positioning of the punch with reference to the work can be secured. For example, in the punching of rivet holes in structural steel, it will be obvious that the rivet holes in corresponding parts must be accurately centered, since otherwise the holes in two parts will not register, and in order to make it possible to punch holes with extreme accuracy the plunger 20 can be lowered by hand, while the ram is out of engagement therewith, so that the central projection or tip *a* of the punch *A* can be positioned with great accuracy on a prick punch hole or other mark on the work *X*, and by means of my construction, the head or plunger remains in this position until engaged by the ram during its downward movement to punch 115 through the work. In order to obtain these 120 125 130

results, I have provided frictional means for supporting the plunger or head 20 in any adjusted position, and also an adjusting device whereby the plunger or head may be moved 5 against the frictional holding means to position the same correctly with reference to the work. As a result of these frictional means, the plunger or head 20 will remain in such position until engaged by the ram. 10 Frictional means of any suitable kind may be employed for holding the plunger or head in this position, those shown in the particular construction illustrated being organized as follows:

15 In order to hold the head or plunger in any desired position, by means of friction, the friction is applied to a drum 65 arranged on one side of the guide member 15, which drum is mounted on a shaft 66 jour- 20 nalled in a guide member 15, and having a pinion at one end thereof which engages with a rack 68 formed in or secured to one of the upwardly extending legs 21 of the plunger, see particularly Figs. 3 and 7. 25 Friction may be applied to the drum 65 by any suitable means, such, for example, as a brake band 70 which extends around the drum 65, brake material or lining 71 being shown interposed between the band 70 and 30 the drum 65. The ends of the band 70 terminate in proximity to each other, one end of the band being fastened to a pin 72 secured in a side wall of the guide member 15 or other fixed part of the machine, and the 35 other end of the brake band being acted upon by means of a spring 73 arranged around a bolt 74 extending through holes in two ends of the brake drum, and an adjustable nut or collar 75 on the bolt 74 may be 40 used for regulating the force exerted by the spring. This force is preferably just enough to overcome the weight of the plunger and the parts mounted thereon. Any 45 other means for frictionally holding the plunger in any position in which it is set may be employed.

The adjusting of the plunger to position the same relatively to the work is preferably also effected through the medium of the 50 shaft 66, pinion 67 and rack 68 and for this purpose a second drum 80 is secured on the shaft 66, and a clamping lever 81 is provided with a substantially circular split portion 82 surrounding the drum 80. The free 55 end of the split portion or clamping member 82 of the lever 81 is connected with a tension member or link 83, which may be pivotally secured to a lug 84 extending outwardly from the free end of the clamping 60 band or part 82 of the lever 81, and the upper end of the tension member 83 is preferably pivoted at 85 to a finger lever 86 pivoted at 87 on the lever 81. Consequently, 65 when an operator grasps the end of the lever 81, his fingers encircle the finger lever 86 and

by pressing this lever toward the end of the lever 81, tension will be applied to the member 83 which will cause the split portion or clamping member 82 of the lever to grip or clamp the drum 80. Consequently, when the lever 81 is in gripping engagement with the drum 80, the swinging of the lever will cause a turning of the shaft 66 against the friction afforded by the brake band 70, so that the plunger may be moved into its desired position relatively to the work. Other means for positioning the plunger against the action of the friction means acting on the plunger may be employed.

As soon as the plunger has thus been accurately positioned relatively to the work, the ram retaining link 35 may be moved out of its retaining position to permit the ram to move the plunger through the work. In order to facilitate the operation of the machine, I have provided means whereby the lever 81 can be used for releasing the ram after the plunger has been set into the desired position, and these means may, for example, be constructed as follows:—A detent 90 releasing or trip lever 88 is pivoted at 89 on one of the side walls 18 of the bearing member 15 for the plunger, the lever extending through a recess 92 in the rear face of front plate 19 of the guide member 15. One end 95 of this lever extends underneath the holding or detent link 35, preferably in rear of the detent plate 37, as is clearly shown in Figs. 1, 2 and 5, and the other end of the lever extends into the path of movement of the lever 81 about the axis of the shaft 66. Consequently, by swinging the lever 81 downwardly into the position shown in dotted lines in Fig. 8, the end of the trip lever 88 is engaged by the hand lever 81, causing the trip lever to swing about its pivot 89, so that the other end of the lever arranged underneath the link 35 is raised to disengage the holding link 35 from its detent plate 37, and thus permit the ram to seat in the plunger. 105 This construction is particularly desirable because it facilitates the operation of the machine, since the operator, by clamping the lever 81 to its drum 80, can move the lever forwardly to adjust the plunger relatively 110 to the work, and when this has been done, the operator relieves the tension on the finger lever 86, and continues the forward movement of the hand lever 81 until this lever strikes the end of the trip lever 88, thus 115 releasing the ram from its inoperative position. Since the longer end of the lever 88 lies below the detent link 35, the lever 88 will fall by gravity into the inoperative position shown in full lines in Fig. 6.

During the use of the machine, the operator may adjust the punch with reference to the work, and then move the hand lever 81 into engagement with the trip lever 88 at any portion of the stroke of the ram or 120

power driven member, and the machine is so organized that the power driven member will not raise the plunger from its adjusted position, even though the ram may be in a position below that at which it can seat on the bearing plate 23 when the trip lever is actuated. Any suitable means may be employed for keeping the ram out of engagement with the tool carrying member until the downward stroke of the ram. In the construction shown, the ram is provided with an inclined or beveled face 90 which is adapted to engage a correspondingly beveled face 91 on the bearing block 23 during the upward stroke of the ram, and the lower extremity of the ram is rounded as shown at 93, and is adapted to fit into the correspondingly rounded portion 28 of the bearing block 23, which rounded face terminates in a projection 94 on the wear block which extends somewhat above the lowest portion of the seat 28 in the bearing block. Consequently, by means of the engagement of the beveled faces 90 and 91, respectively, of the ram and bearing block of the plunger, and of the rounded lower face 93 of the ram with the upwardly extending projection 94 of the bearing block, the upwardly extending arms 50 of the ram will be kept out of engagement with the set screws 53. In order to further insure against lifting of the head or plunger by the ram during the upward stroke thereof before the ram is properly seated in the plunger, the front face or edge of each of the upwardly extending arms 50 is preferably rounded or beveled as shown at 95, and the portions of the sides 21 of the head or plunger which extend over the recess 52 therein, are also provided with beveled faces 96, see particularly Fig. 7. Consequently, when the rounded or beveled faces 95 of the arms strike either the set screws 53 or the beveled face 96 of the sides of the plunger, the upwardly extended lifting arms 50 of the ram will be pushed backwardly against the action of the spring 58, so that no raising of the plunger results. However, when the ram moves downwardly, the lifting arms 50 can readily yield against the action of the spring 58 and permit the ram to enter into its seated position in which the rounded lower face thereof engages the seat 28 of the bearing plate at which time the lifting arms 50 will also snap forwardly into their operative positions to cooperate with the set screws 53 to raise the plunger.

Means are preferably provided whereby the lever 81 will be swung out of the position shown in dotted lines in Fig. 8, after this lever is released by the operator, and for this purpose a plunger 97 is arranged in a hole or recess in the lever 81, see particularly Fig. 9, which plunger is pressed into engagement with the drum 80 by means of the spring 98. There is just enough fric-

tion between the plunger 97 and the drum 80 to cause the lever 81, when released by the operator, to swing with the drum, and, consequently, upon the upward movement of the head or plunger 21, the rack 68 causes the pinion 67 to rotate the shaft 66 in a direction opposite to that in which the shaft is turned for adjusting the plunger, and this movement of the shaft 66 causes the lever 81 to be returned to its upright position as shown in full lines in Fig. 8, whereupon the same is ready to be again actuated by the operator. This plunger 97 also moves the hand lever 81 positively out of engagement with the trip lever 88, thus permitting the detent link 35 to function after each operation of the machine.

When my invention is applied to a machine in which the work is punched, cut or sheared, after the punch or tool has sheared the work, the last portion of the downward stroke of the punch frequently results in a sudden jerking of the plunger downwardly after the resistance of the work has ceased, this being particularly true when a machine is used in connection with hard metal. In order to prevent this downward jerking of the plunger, shock absorbers or bumpers are employed, which yieldingly oppose the movement of the plunger, just as the punch shears the metal. In the construction shown for this purpose, a pair of shock absorbers 99 are provided which may be made of rubber or other resilient material, and which in the construction shown rest on the upper surface of a shelf or ledge 100 secured to the upper edge of one of the side walls 18 of the plunger guide, the ledge or shelf 100 being secured to the side walls 18 by means of bolts 101, or the like. The inner portion of the shelf or ledge 100 extends over one of the sides 21 of the head or plunger, and rods 102 secured at their lower ends in one of the sides 21 of the head or plunger extend through the ledge 100 and through the bumpers or shock absorbers 99 and are provided at their upper ends with suitable stops, such, for example, as a pair of lock nuts 103, which are so positioned that they engage the upper ends of the bumpers or shock absorbers 99 just as the punch has sheared the metal. Consequently, further downward movement of the punch after shearing of the metal is effected against the resistance offered by the bumpers or shock absorbers 99, and the nuts 103 are adjustable so that they can be correctly positioned with reference to the bumpers or shock absorbers.

Means are also preferably employed for limiting the upward movement of the head or plunger 20, since it will be obvious that if this head is raised to a point beyond that at which the lower end of the ram 27 may seat on the bearing block 23 of the head or

6
 plunger, the ram will not be able to effect downward movement of the plunger. In order to limit this movement a stop bolt or screw 105 is provided in the ledge or shelf 5 100, the stop screw preferably engaging in a threaded hole in the shelf 100, and a lock nut 106 securely holds the screw in its adjusted position. The lower end of this screw is adapted to engage the upper end of 10 one of the upwardly extending arms 21 of the head or plunger, and this screw is also adjustable so that the upper limit of the movement of the head or plunger can be accurately controlled as desired.

15 In the operation of the punching machine described, the operator places the work X on the die B and then grasps the hand lever 81 and finger lever 86, pressing the finger lever toward the hand lever to clamp the 20 hand lever on the drum 80. Upon drawing the hand lever forwardly, the drum and shaft 66 will be turned causing the pinion 67 to cooperate with the rack 68 to move the tool carrying member 20 downwardly, and 25 at the same time the tip a of the punch is accurately positioned with reference to the work X. When this has been done, the finger lever 86 is released to permit the hand lever to be turned about the drum 80 with- 30 out turning the drum, and the hand lever 81 is pulled forwardly to strike the trip lever 88 which raises the latch or detent link 35 out of engagement with the holding plate 37, and permits the spring 39 to move the 35 ram 27 forwardly. This forward movement of the ram during the downward stroke thereof will cause the same to seat on the plunger or head as shown in Fig. 1, whereupon the continued downward movement of 40 the ram will force the plunger downwardly and the punch A through the work. Upon the upward or return stroke of the ram, the arms 50 thereof will engage the set screws 53 and raise the head or plunger un- 45 til the knock-out projection 42 of the ram engages the rearwardly projecting portion of the lever 43, whereupon the ram will be swung about its pivot 29 out of its operative connection with the head or plunger and 50 the notched portion 36 of the detent link 35 will again engage the holding plate 36, so that only one working stroke of the tool carrying head results from the releasing of the 55 detent lever, and the machine is then ready to be again actuated. The operator, after having pressed the hand lever 81 into engagement with the trip lever 88, releases the hand lever, and the friction of the plunger 97 in the hand lever 81 bearing on the drum 80 60 will cause the hand lever again to swing into its upper or upright position during the upward stroke of the head or plunger 20, so that the machine is ready for the next operation. If the trip lever is actuated during 65 the time that the ram 27 is below its seat-

ing position with reference to the plunger or head, the ram will move upwardly without raising the head 20, as has been described, and consequently, the tool or punch A will not be moved out of the position into which 70 it has been set.

The machine described has the advantage that the tool carrying head, after having been set into its correct position, will be positively held in this position by the friction drum 65 and band 70, and the desired friction can be very quickly adjusted by merely adjusting the tension of the spring 73. Furthermore, the adjusting of the 75 punch with reference to the work and the 80 actuating of the trip lever to start the operation of the machine can be done by practically a continuation of the same movement of one hand of the operator, leaving the other hand free to position or hold the work. The mechanism is so constructed that none 85 of the parts are subject to excessive wear, and those parts which are subject to wear are made adjustable, so that any wearing of 90 these parts can be readily compensated for. Also by adjusting the knock-out lever 43, the 95 machine may be controlled so that a knocking out of the ram takes place at different portions of the stroke of the tool carrying head. For example, when working on thin 100 metal, the knock-out lever 43 can be adjusted so that the punch is raised only a slight distance above the metal, thus requiring very little downward movement of the 105 tool carrying head by means of the hand lever 81, and when working on thicker metal, an upward adjustment of the rearward projection of the knock-out lever 43 can be made. The shock absorber or bumpers 99 110 save much of the wear and tear on the machine in that they cushion or yieldingly resist further downward movement of the 115 plunger at the time that the metal is sheared.

I claim as my invention:—

1. A punching machine including a reciprocatory tool carrying head, a power driven member adapted to be connected with and disconnected from said head to impart movement thereto, and frictional means for holding said head in different set positions when disconnected from said power driven member.

2. A punching machine including a reciprocatory tool carrying head, a power driven member adapted to be connected with said head to impart movement thereto and to be disconnected from said head, frictional means for holding said head in different set positions when disconnected from said power driven member, and hand operated means 120 for moving said head against the action of said friction means.

3. A punching machine including a reciprocatory tool carrying head, a power driven member adapted to be connected with said 125

head to impart movement thereto, and adjustable friction means adapted to counterbalance the weight of said head when disconnected from said power driven member.

- 5 4. A punching machine including a reciprocatory tool carrying head, a power driven member adapted to be connected with said head to impart movement thereto, frictional means for holding said head in different set 10 positions when disconnected from said power driven member, means for adjusting said frictional means to vary the extent to which the same resists movement of said head, and hand operated means for moving said head 15 against the action of said frictional means when said head is disconnected from said power driven member.

5. The combination of a reciprocatory tool carrying member, a power driven member 20 adapted to be connected with said tool carrying member, and a friction drum which is rotated when said tool carrying member is reciprocated and which holds said tool carrying member in any position in which the 25 same is set when disconnected from said power driven member.

6. The combination of a reciprocatory tool carrying member, a power driven member adapted to be connected with said tool carrying member, a drum which is rotated when said tool carrying member is reciprocated, and friction means acting on said drum to counterbalance the weight of said tool carrying member.

7. The combination of a reciprocatory tool carrying member, a power driven member adapted to be connected with said tool carrying member, a friction drum which is rotated when said tool carrying member is reciprocated and which holds said tool carrying member in any position in which the same is set when disconnected from said power driven member, and means for turning said friction drum against the friction to vary the position of said tool carrying member.

8. The combination of a reciprocatory tool carrying member, a power driven member adapted to be connected with said tool carrying member, a friction drum which is rotated when said tool carrying member is reciprocated and which holds said tool carrying member in any position in which the same is set when disconnected from said power driven member, and a clamping member adapted to releasably engage a part connected with said friction drum to turn the same for adjusting said tool carrying member relatively to the work.

60 9. The combination of a reciprocatory tool carrying member, a power driven member adapted to be connected with said tool carrying member, a friction drum connected with said tool carrying member and rotated by the reciprocatory movement of said tool

carrying member and which serves to hold said tool carrying member in any position in which the same is set when disconnected from said power driven member, a shaft on which said drum is mounted, and a clamping lever adapted to be moved into holding engagement with said shaft for turning said friction drum to adjust said tool carrying member.

10. The combination of a reciprocatory tool carrying member, a power driven member adapted to be connected with and disconnected from said tool carrying member, a rack movable with said tool carrying member, a pinion engaging said rack, and friction means cooperating with said pinion to support the tool carrying member in any position in which the same is set when disconnected from said power driven member.

11. The combination of a reciprocatory tool carrying member, a power driven member adapted to be connected with and disconnected from said tool carrying member, a rack movable with said tool carrying member, a pinion engaging said rack, friction means cooperating with said pinion to support the tool carrying member in any position in which the same is set when disconnected from said power driven member, and means connected with said pinion for turning the same against the action of said friction means to adjust the tool carrying member relatively to the work.

12. The combination of a reciprocatory tool carrying member, a power driven member adapted to be connected with and disconnected from said tool carrying member, a rack movable with said tool carrying member, a pinion engaging said rack, friction means cooperating with said pinion to support the tool carrying member in any position in which the same is set when disconnected from said power driven member, a shaft on which said pinion is mounted, a friction drum mounted on said shaft for holding said tool carrying member in any position in which the same is set when disconnected from said power driven member, and clamping means adapted to engage said shaft for turning the same against the action of said friction drum to adjust said tool carrying member.

13. The combination of a reciprocatory tool carrying member, a power driven member adapted to be connected with said tool carrying member, friction means for holding said tool carrying member in any position in which the same is set when disconnected from said power driven member, a rotary member connected with said tool carrying member and on which said friction means are mounted, a clamping lever adapted to clamp said rotary member for adjusting the position of said tool carrying member, and a frictional connection between said

clamping lever and said rotary member whereby the movement of said tool carrying member away from the work by said power driven member causes the clamping lever to 5 return to its initial position.

14. The combination of a reciprocatory tool carrying member, a power driven member adapted to be connected with said tool carrying member, means for holding said 10 power driven member out of engagement with said tool carrying member, and means for adjusting said tool carrying member when said power driven member is out of engagement therewith, a part of said adjusting means being movable into a position to release said holding means to permit said power driven member to engage said tool carrying member.

15. The combination of a reciprocatory tool carrying member, a power driven member adapted to be connected with said tool carrying member, means for holding said power driven member out of engagement with said tool carrying member, and means 25 for adjusting said tool carrying member when said power driven member is out of engagement therewith, a rotary member connected with said tool carrying member, and a lever adapted to engage said rotary member for turning the same to adjust said tool carrying member, and adapted to be moved about the axis of said rotary member to release said holding means.

16. The combination of a reciprocatory tool carrying member, a power driven member adapted to be connected with said tool carrying member, means opposing the weight of said tool carrying member, means for holding said power driven member out of engagement with said tool carrying member, means including a lever adapted to be actuated for adjusting the position of said tool carrying member, said lever being adapted to be disconnected from said tool carrying 40 member and to be moved into a position to release said holding means to permit said power driven member to engage said tool carrying member.

17. The combination of a reciprocatory tool carrying member, a power driven member adapted to be connected with said tool carrying member, a rotatable member connected with said tool carrying member and rotated by the reciprocatory movement thereof, a gripping lever adapted to engage said rotary member for turning the same to adjust said tool carrying member, means for holding said power driven member out of engagement with said tool carrying member, 55 said lever being adapted to be moved into a position to release said holding member, and a frictional engagement between said lever and said rotary member whereby the movement of said tool carrying member in 60 a direction away from the work causes said

rotary member to move said lever into its initial position and out of engagement with said holding means.

18. The combination of a reciprocatory tool carrying member, a power driven member adapted to be connected with and disconnected from said tool carrying member to move the same through a power stroke and a return stroke, and means with which said power driven member moves into engagement at the completion of its return stroke for moving said power driven member out of engagement with said tool carrying member.

19. The combination of a reciprocatory tool carrying member, a power driven member adapted to be connected with and disconnected from said tool carrying member to move the same through a power stroke and a return stroke, means with which said power driven member moves into engagement at the completion of its return stroke for moving said power driven member out of engagement with said tool carrying member, and a releasable holding member for holding said power driven member out of engagement with said tool carrying member.

20. In a machine of the kind described, the combination of a reciprocatory tool carrying member, a power driven member adapted to be connected with and disconnected from said tool carrying member, a fixed part on said machine cooperating with a part on said power driven member for moving said power driven member out of engagement with said tool carrying member after said power driven member has moved said tool carrying member out of engagement with the work and a latch pivoted on said power driven member and adapted to engage a fixed part of the machine for holding said power driven member in its inoperative position.

21. In a machine of the kind described, the combination of a reciprocatory tool carrying member, a power driven member adapted to be connected with said tool carrying member to move the same through a working stroke and a return stroke, means for yieldingly urging said power driven member into engagement with said tool carrying member, a detent member for normally holding said power driven member out of engagement with said tool carrying member and which may be released at will to permit said means to move said power driven member into engagement with said tool carrying member, and cooperating means on said machine and said power driven member to move said power driven member out of engagement with said tool carrying member and to place said detent member into its holding position.

22. In a machine of the kind described, the combination of a reciprocatory tool carrying

member, a power driven member adapted to be connected with and disconnected from said tool carrying member to move said tool carrying member through a working stroke 5 and a return stroke, and means engaged by a part of said power driven member during its return stroke for moving said power driven member out of engagement with said tool carrying member, said means being adjustable to engage said power driven member at different portions of the return stroke thereof.

23. In a machine of the kind described, the combination of a reciprocatory tool carrying member, a power driven member adapted to be connected with and disconnected from said tool carrying member to move said tool carrying member through a working stroke and a return stroke, a fixed part on said 10 machine and a part on said power driven member which are adapted to engage for moving said power driven member out of engagement with said tool carrying member during the return stroke thereof, and means 15 for adjusting one of said parts relatively to the other to vary the portion of the return stroke at which said power driven member is moved out of engagement with said tool carrying member to vary the position of the 20 tool carrying member with reference to the work.

24. In a machine of the kind described, the combination of a reciprocatory tool carrying member, a pivoted power driven member adapted to swing into and out of engagement with said tool carrying member to move said tool carrying member through a working stroke and a return stroke, and a part engaged by said power driven member 25 during its return stroke which positively swings said power driven member out of engagement with said tool carrying member to determine the rest position of said tool carrying member.

25. In a machine of the kind described, the combination of a reciprocatory tool carrying member, a pivoted power driven member adapted to swing into and out of engagement with said tool carrying member 30 to move said tool carrying member through a working stroke and a return stroke, a part on said machine adapted to engage a part of said power driven member during the return stroke thereof to move said power driven member out of engagement with said tool carrying member, and means for adjusting said part on said machine to cause said power driven member to move out of engagement with said tool carrying member at 35 different portions of the return stroke thereof to determine the rest position of said tool carrying member.

26. In a machine of the kind described, the combination of a reciprocatory tool carrying member, a pivoted power driven member

adapted to swing into and out of engagement with said tool carrying member to move said tool carrying member through a working stroke and a return stroke, a knock out lever pivoted on a fixed part of the machine and adapted to engage a part of said power driven member to move the same out of engagement with said tool carrying member during the return stroke thereof, and means for adjusting said lever to vary the portion of the return stroke at which the power driven member moves out of engagement with said tool carrying member to determine the rest position of said tool carrying member.

27. The combination of a reciprocatory tool carrying member having a pair of upwardly extending arms spaced apart, a pivoted power driven member adapted to swing into and out of the space between said arms and to be connected with said tool carrying member for actuating the same when in a position between said arms, and a holding member extending between said arms and pivoted to said power driven member and having a part for positively engaging a fixed part to releasably hold said power driven member out of engagement with said tool carrying member.

28. The combination of a reciprocatory tool carrying member having a base portion and upwardly extending arms spaced apart, a power driven member adapted to swing into the space between said arms and to seat against the base portion thereof to move 100 said tool carrying member through its working stroke, cooperating parts on said arms and said power driven member for moving said tool carrying member through its return stroke and yielding means for normally 105 holding said parts on said power driven member in positions to engage the parts on said arms.

29. The combination of a reciprocatory tool carrying member having side portions 110 spaced apart and a connecting base portion, a power driven member adapted to enter between said side portions of said tool carrying member and to seat on said base portion, arms on said power driven member adapted to engage parts on the side portions of said tool carrying member when said power driven member is seated on the base portion of the tool carrying member said arms being movable relatively to said power driven member, and yielding means for normally holding said arms in positions to engage said parts on said side portions.

30. The combination of a reciprocatory tool carrying member, a power driven member means for moving said power driven member into engagement with said tool carrying member, a rigid part on said power driven member engaging with a rigid fixed part for positively moving said power 125

driven member out of engagement with said tool carrying member after the completion of a working stroke, means for adjusting said tool carrying member relatively to the work when said power driven member is out of engagement therewith, and means for holding said power driven member out of engagement with said tool carrying member except when said power driven member is moving in a direction to move said tool carrying member first in its working stroke.

31. The combination of a reciprocatory tool carrying member movable through a working stroke and a return stroke, a reciprocatory power driven member adapted to be connected with said tool carrying member for actuating the same, means for adjusting said tool carrying member relatively to the work when said power driven member is out of engagement therewith, said power driven member having a part adapted to move said tool carrying member through its working stroke and another part adapted to move said tool carrying member through its return stroke, and means for preventing said other part from engaging said tool carrying member until after the part of said power driven member which moves said tool carrying member through its working stroke has engaged said tool carrying member.

32. The combination of a reciprocatory tool carrying member movable through a working stroke and a return stroke, a reciprocatory power driven member adapted to be connected with said tool carrying member for actuating the same, means for adjusting said tool carrying member relatively to the work when said power driven member is out of engagement therewith, a part on said power driven member which seats on said tool carrying member to move said tool carrying member through its working stroke, arms on said power driven member which engage parts of said tool carrying member to move said tool carrying member through its return stroke, and means for preventing said arms from engaging said tool carrying member until after the parts of said members which move said tool carrying member through its working stroke are in engagement.

33. The combination of a reciprocatory tool carrying member adapted to move through a working stroke and a return stroke, a reciprocatory power driven member having a part adapted to be moved into and out of engagement with said tool carrying member and adapted to move the same through its working stroke, parts on said power driven member adapted to engage parts on said tool carrying member for moving said tool carrying member through its return stroke, and means for holding said last mentioned parts out of engagement un-

til after said parts which move said tool carrying member through its working stroke are in engagement.

34. The combination of a tool carrying member movable through a working stroke and a return stroke, a power driven member movable into and out of engagement with said tool carrying member, cooperating faces on said power driven member and said tool carrying member for moving said tool carrying member through its working stroke when said power driven member is in engagement with said tool carrying member, and parts on said power driven member which are adapted to engage parts on said tool carrying member for moving said tool carrying member through its return stroke, and means for holding said parts on said power driven member out of engagement with the corresponding parts on said tool carrying member until the faces of said two members are in engagement.

35. The combination of a tool carrying member movable through a working stroke and a return stroke, a power driven member movable into and out of engagement with said tool carrying member, cooperating faces on said power driven member and said tool carrying member for moving said tool carrying member through its working stroke when said power driven member is in engagement with said tool carrying member, and pivoted arms on said power driven member which are adapted to swing into engagement with cooperating parts on said tool carrying member after said faces of said power driven member and tool carrying member are in engagement.

36. The combination of a tool carrying member movable through a working stroke and a return stroke, a power driven member movable into and out of engagement with said tool carrying member, cooperating faces on said power driven member and said tool carrying member for moving said tool carrying member through its working stroke when said power driven member is in engagement with said tool carrying member, arms pivotally mounted on said power driven member and adapted to engage cooperating parts on said tool carrying member for moving said tool carrying member through its return stroke, and means for yieldingly holding said arms in their operative position, said means permitting said arms to swing out of their operative position until the faces of said power driven member and said tool carrying member are in engagement.

37. The combination of a tool carrying member movable through a working stroke and a return stroke, a power driven member movable into and out of engagement with said tool carrying member, cooperating faces on said power driven member and said tool carrying member for moving said tool car-

rying member through its working stroke when said power driven member is in engagement with said tool carrying member, adjustable parts on said tool carrying member, and parts on said power driven member adapted to engage said adjustable parts on said tool carrying member for moving said tool carrying member through its return stroke.

10 38. The combination of a tool carrying member movable through a working stroke and a return stroke, a power driven member movable into and out of engagement with said tool carrying member, cooperating faces 15 on said power driven member and said tool carrying member for moving said tool carrying member through its working stroke when said power driven member is in engagement with said tool carrying member, 20 adjustable parts on said tool carrying member, pivoted arms on said power driven member, and resilient means tending to move said arms into position to engage the said adjustable parts on said tool carrying member for moving said tool carrying member through its return stroke.

30 39. The combination of a reciprocatory tool carrying member, a power driven member adapted to move into engagement with said reciprocatory member to move the same through a working stroke and a return stroke, means for adjusting said tool carrying member relatively to the work while said power driven member is out of engagement 35 therewith, and inclined cooperating faces on said members which prevent said power driven member from engaging said tool carrying member while said power driven member is moving in the direction of the return 40 stroke.

40 40. The combination of a reciprocatory tool carrying member, a power driven member movable into a position out of engagement with said tool carrying member and into engagement with said tool carrying member to actuate the same, a detent link pivoted on said power driven member and adapted to engage a fixed part of the machine to hold said power driven member out 45 of engagement with said tool carrying member, and means for moving said detent link out of its holding position to permit said power driven member to engage said tool carrying member.

55 41. The combination of a reciprocatory tool carrying member, a power driven member movable into a position out of engagement with said tool carrying member and into engagement with said tool carrying member to actuate the same, a detent link pivoted on said power driven member and adapted to engage a fixed part of the machine to hold said power driven member out

of engagement with said tool carrying member, means for moving said detent link out 65 of its holding position to permit said power driven member to engage said tool carrying member, and means upon the completion of the return stroke of said tool carrying member to move said power driven member out 70 of engagement with said tool carrying member and to return said detent link to its holding position.

42. The combination of a reciprocatory tool carrying member, a power driven member movable into a position out of engagement with said tool carrying member and into engagement with said tool carrying member to actuate the same, a detent link pivoted on said power driven member and adapted to engage a fixed part of the machine to hold said power driven member out 80 of engagement with said tool carrying member, means for moving said detent link out of its holding position to permit said power driven member to engage said tool carrying member, means for adjusting said tool carrying member with reference to the work when said power driven member is out of engagement therewith, and a connection between said adjusting means and said detent link for moving said detent link out of its holding position upon the completion of the adjustment, to permit said power driven member to actuate said tool carrying member.

43. The combination of a reciprocatory tool carrying member, a power driven member movable into a position out of engagement with said tool carrying member and into engagement with said tool carrying member to actuate the same, a detent link pivoted on said power driven member and adapted to engage a fixed part of the machine to hold said power driven member out 100 of engagement with said tool carrying member, means for moving said detent link out of its holding position to permit said power driven member to engage said tool carrying member, means for adjusting said tool carrying member with reference to the work when said power driven member is out of engagement therewith, a connection between said adjusting means and said detent link for moving said detent link out of its holding position upon the completion of the adjustment, to permit said power driven member to actuate said tool carrying member.

105 44. The combination of a reciprocatory tool carrying member, a power driven member movable into a position out of engagement with said tool carrying member and into engagement with said tool carrying member to actuate the same, a detent link pivoted on said power driven member and adapted to engage a fixed part of the machine to hold said power driven member out 110 of engagement with said tool carrying member, means for moving said detent link out of its holding position to permit said power driven member to engage said tool carrying member, means for adjusting said tool carrying member with reference to the work when said power driven member is out of engagement therewith, a connection between said adjusting means and said detent link for moving said detent link out of its holding position upon the completion of the adjustment, to permit said power driven member to actuate said tool carrying member, and means upon the completion of the return stroke for moving said power driven member out of engagement with said tool carrying member and for permitting said detent link to move into its holding position.
